(Cl. D45—4)

To all whom it may concern:

Be it known that we, Joseph Rosenberg and Francis D. Byrne, citizens of the United States, and residing, respectively, in New York city, county of Kings, and State of New York, and in West Orange, county of Essex, and State of New Jersey, have invented a new, original, and ornamental Design for a Bracelet or Similar Article, of which the following is a specification, reference being had to the accompanying drawing, forming part thereof.

We claim:

The ornamental design for a bracelet or similar article, substantially as shown.

JOSEPH ROSENBERG.
